US00D743096S

(12) **United States Design Patent**
Patton et al.

(10) **Patent No.:** **US D743,096 S**
(45) **Date of Patent:** **** Nov. 10, 2015**

(54) **ELECTRIC, TAPER CANDLE**

(71) Applicant: **Luminara Worldwide, LLC**, Eden Prairie, MN (US)

(72) Inventors: **Douglas Patton**, Irvine, CA (US); **Jeffrey Thompson**, Huntington Beach, CA (US)

(73) Assignee: **Luminara Worldwide, LLC**, Eden Prairie, MN (US)

(**) Term: **15 Years**

(21) Appl. No.: **29/533,862**

(22) Filed: **Jul. 22, 2015**

(51) **LOC (10) Cl.** **26-99**

(52) **U.S. Cl.**

USPC **D26/154**

(58) **Field of Classification Search**
